CHART RECORDER

Paul L. Stone, Meadowbrook, Pa., assignor to Honeywell
Inc., Minneapolis, Minn., a corporation of Delaware

Filed Apr. 15, 1966, Ser. No. 1,903

Term of patent 14 years

(Cl. D26—14)

FIG. 1

FIG. 2

FIG. 1 is a front elevational view of chart recorder, showing my new design wherein the indicating ribbons associated with each overlapping pen arm have been lined to indicate color and the diagonal lines upon the central portion of the door indicate transparency;

FIG. 2 is a perspective view thereof wherein the indicating ribbons associated with each overlapping pen arm have been lined to indicate color and the diagonal lines upon the central portion of the door indicate transparency.

The bottom, not shown, is substantially the same in appearance as the top.

The right side, not shown, is substantially the same in appearance as the left side.

The rear, not shown, is substantially flat and unornamented.

I claim:

The ornamental design for chart recorder, as shown and described.
